COUNTER TOP COOKING UNIT

Emery J. Poracki, South Gate, Calif., assignor to O'Keefe
of California

Application January 13, 1958, Serial No. 49,238

Term of patent 14 years

(Cl. D81—25)

FIG. 1.

FIG. 2.

FIG. 3.

Fig. 1 is a perspective view of a counter top cooking unit showing my new design;

Fig. 2 is a top plan view; and

Fig. 3 is a sectional view taken on the broken line 3—3 of Fig. 1.

I claim:

The ornamental design for a counter top cooking unit, as shown.
